1893

HOWE,
SKIRT-BINDING.
No. 55

Be it known, that I, John C. Stinson, a citizen of the United States, and a resident of New York, and ^{in the} county of New York, and ^{in the} state of New York, have invented certain new and useful improvements in Skirt-Bindings, of which the following is a specification.

This invention relates to improvements in skirt-bindings, and its object is to provide a stiffening-tape with a pocket for the reception of a stiffening-tape and with a suitable protecting-edging in a simple and convenient manner.

In the accompanying drawings, Figure 1 is a perspective view of a part of the lower portion of my skirt-binding. Figure 2 is a cross-sectional view of my skirt-binding. Figure 3 is a modification of Figure 2.

In the accompanying drawings, Figure 1 is a perspective view of a part of the lower portion of a skirt, showing my skirt-binding. Figure 2 is a diagrammatic cross-sectional view of my skirt-binding. Figure 3 is a modification of Figure 1, showing stiffening material.

In the a perspective view, 2 is a diagrammatic cross-section of a skirt, showing in 2, showing stiffening. Fig. 3 is a modification 1 represents a portion of a skirt which is sewed the binding 2. The binding 2 is composed of three parts—namely, the part 3, which consists of a strip of any suitable “backing” material, the part 4, which is a strip of velvet or other suitable material and which may be called the “covering-strip,” said strip having

its edges hemmed and attached to the back-
ing-strip by the stitches 5 and 6, and the
“edging-strip” 7, which consists of a cord of
the pile fabric passed in a spiral manner through
the lower edge of the backing-strip 3. Be-
tween the velvet strip 4 and the backing-strip
3 is a casing or pocket 8, adapted to hold a
stiffening-strip 8, as shown in Fig. 3.

Having described my invention, what
claim as new, and desire to secure by Lette
Patent, is—

An article of manufacture, a skirt-bi
ring, comprising a backing-strip, a cover
strip, and a stiffening-strip, the back-
ing-strip being attached to its upper edge and
the cover strip being attached to the back-
ing-strip, the cover strip being attached to the
upper edge of the stiffening-strip, the
stiffening-strip being attached to the back-
ing-strip.

Having described my invention, I claim as new, and desire to secure the same under the laws of the United States, as follows:

As an article of manufacture, a skirt-binding comprising a backing-strip, a cover-strip turned over at its upper edge and over at its lower edge against the backing-strip and sewed to said backing-strip, leaving a space between the strips for the reception of a binding-tape, and a protecting edging of a flexible material secured to the lower edge of the said backing-strip.
